UNITED STATES PATENT OFFICE.

WILLIS A. ALLEN, OF PALMYRA, WISCONSIN, ASSIGNOR OF ONE-HALF TO
NELSON WILLIS, OF SAME PLACE.

HARNESS-BUCKLE.

SPECIFICATION forming part of Letters Patent No. 294,561, dated March 4, 1884.

Application filed October 22, 1883 (No model.)

To all whom it may concern:

Be it known that I, WILLIS A. ALLEN, of Palmyra, in the county of Jefferson, and in the State of Wisconsin, have invented certain new and useful Improvements in Harness-Buckles; and I do hereby declare that the following is a full, clear, and exact description thereof.

My invention relates to harness-buckles, and will be fully described hereinafter.

10 In the drawings, Figure 1 is a top view of my improved buckle. Fig. 2 is a vertical section of same through center. Fig. 3 is the under side view of same, and Fig. 4 is an elevation of my improved buckle with the parts detached.

15 The buckle consists of two separate pieces, A being the looped link, on the rear cross-bar of which the tug is hinged. Its sides *b b* are curved up to the top pressure-bar, *c*, and thence are curved down to the bottom pressure-bar, *d*, thus forming the double loop for the passage of the buckling-strap. B is the tongue-bearing frame or buckle proper. It has the rear cross-bar, *e*, connecting the sides *f f*. 20 These are curved down to be connected again by cross-bar *g* and form the rear loop, *h*. Extending forward, said sides *f f* are curved up on a gentler line, to be connected again on about the same plane as the cross-bar *e* by 25 the front cross-bar, *k*. On the under side of said cross-bar *k* a lug, *l*, is formed, which constitutes the buckle-tongue. Said sides *f f* are notched at *i i*, to allow of the insertion of the looped link A inside the loops of the buckle-frame B. Said frame B may be provided with strengthening-pieces *m m* for its sides *f f*, and the lip *n* for the tongue bar *k*.

30 The manipulation of my improved buckle is as follows: The looped link A having been fitted to the end of the strap as ordinary buckles are, it is inserted, curved side up, into

the loop *h* of said buckle-frame B and pushed clear through, until the cross-bar *g* of said frame B rests against the leather embracing the bar *a* of looped link A. The tug end is 45 then passed in the front loop of said link A and pushed past the rear loop, *h*, of the buckle-frame B, until the tongue *k* is opposite the hole of the strap in which it is desired to make the connection. Said tongue *k* being then pressed 50 down in the hole, the buckling is effected.

Having thus described my invention, what I claim as new, and desire to secure by Letters Patent, is—

1. A harness-buckle consisting of a curved 55 loop-link having cross-bars, the lower of which is adapted to receive and hinge a tug or strap, in combination with a tongue-bearing frame, with rear cross-bar and downwardly-curving sides connected by another cross-bar, and thence extending forward with an upward curve, and then again connected by a front cross-bar on substantially the same plane as the rear cross-bar, and above the plane of the intermediate cross-bar, substantially as set forth. 60

2. In a harness-buckle, the strap-link A, having the curved sides *b b*, the hinging-bar *a*, and pressure-bars *c* and *d*, in combination with the tongue-bearing frame B, having notched sides *f f*, cross-bars *e* and *g*, forming loop *h*, 70 and cross-bar *k*, with lug *l*, substantially as shown and described, and for the purpose set forth.

In testimony that I claim the foregoing I have hereunto set my hand, at Milwaukee, in 75 the county of Milwaukee and State of Wisconsin, in the presence of two witnesses.

WILLIS A. ALLEN.

Witnesses:

STANLEY S. STOUT,
M. KAUMHEIMER.
